UNITED STATES PATENT OFFICE.

DEIANA DOMENICO, OF SAN FRANCISCO, CALIFORNIA.

POWER-GENERATING APPARATUS.

1,385,526.

Specification of Letters Patent. Patented July 26, 1921.

Application filed December 27, 1920. Serial No. 433,178.

To all whom it may concern:

Be it known that I, DEIANA DOMENICO, a subject of the King of Italy, residing at the city and county of San Francisco and State 5 of California, have invented certain new and useful Improvements in Power-Generating Apparatus, of which the following is a specification.

The present invention relates to improvements in apparatus for obtaining power from the movements of air due to differences in temperature, the object of the invention being to provide such an apparatus by which power may be obtained very economically.

10 The invention consists broadly of an apparatus or device in which the changes in temperature of a current of air in an air canal or channel cause a draft or an air current to flow from the lower extremity of the 15 air canal to the top, and in its passage actuates a power wheel. The channel or canal consists of branches opening to the atmosphere at a low level, and which are covered with earth and are subject to the heat of the 20 earth, they opening into a cylinder of large diameter, in which is rotatably mounted a smaller cylinder, mounting vanes between the surface of the two cylinders so as to provide a running fit or joint. By heating the 25 air above the small cylinder to permit the sudden and rapid expansion, the air current will become swifter through the passage between the cylinders, and, of course, will turn the power wheel cylinder that 30 much faster.

The longer the conduit is, the greater will be the speed of the air current, the height being limited only by the limitations of 35 human construction. The branches immersed in the earth also may be as numerous as desired within the limitation of human 40 construction. These branches to obtain the maximum efficiency therefrom should be of a curved construction leading down from 45 the cylinders through an earth mound and opening at the base of the mound so that there is an elevation between the level at which the branches open into the atmosphere and the level where the branches open into 50 the cylinder. But this is not absolutely necessary. The current through these branches must be controlled so that at any time any 55 number of them may be closed and thereby cut off the current. The number of the branches should never be less than four, so that there may be one exposed at each 45

degrees. These branches immersed in the earth as they are, will become heated thereby causing the air to flow from the lower end to the upper forming the first current. 60

With the above mentioned and other objects in view, the invention consists in the novel construction and combination of parts hereinafter described, illustrated in the accompanying drawings, and set forth in the 65 claims hereto appended, it being understood that various changes in the form, proportion, size and minor details of construction within the scope of the claims may be resorted to without departing from the spirit 70 or sacrificing any of the advantages of the invention.

In the accompanying drawings, Figure 1 is a vertical sectional view of a unit of my improved apparatus, 75

Figs. 2 and 3 are horizontal sections on the lines 2—2, 3—3 of Fig. 1,

Fig. 4 is a side view of a cylindrical motor,

Fig. 5 is a sectional view showing a shaft and ball bearing therefor, 80

Fig. 6 is a horizontal view on the line 6—6 of Fig. 5.

For clearness of apprehension of my invention, I shall first describe in detail a single unit thereof and will then describe the 85 manner in which said units are assembled to form a complete apparatus.

Referring to the drawings, and especially to Figs. 1 and 2 thereof, 1 indicates tubes located in the ground and extending obliquely 90 to the surface of the ground from points as low as are convenient beneath said surface, and opening at their lower ends into subterranean passages 2 through which air can flow. Said lower ends can be closed 95 when desired by gate 3. Said tubes converge at their upper ends and each tube terminates in an upper outlet 4 which outlets are in the form of arcs of a circle about a common center, each occupying about one-fourth of the circumference of said circle. Consequently, said slots register with correspondingly shaped slots 5 in a horizontal plate 6 which register with the annular or contracted air space 7 between the round portion of a vertically disposed cylinder 8 and a cylindrical casing 9 coaxial with the cylinder 8, said casing being supported on said plate 6 outside said slots and being secured in place by a ring 11 engaging its 100 upper edge, said ring being held by means of tie-rods 12, passing through said plate

and having nuts 13 upon their lower ends. Within the cylinder 8 and secured thereto are horizontally extending upper and lower disks 14 and through central holes in said 5 disks extends a shaft 15 secured to said disk. From said cylinder 8 extend the longitudinally disposed helical vanes 16, all of the same width. The free edges of the vanes extend into close proximity to the inner surface 10 of the casing 9 to prevent the air passing between the edge thereof and the casing surface resulting in a consequent loss of power. From the construction thus far described, it results that any air currents passing 15 upward through the tubes 1 would flow out through the slots 5 and impinge against said helical vanes 16, and would impart rotation to said cylinder 8 about its axis.

The shaft 15 rotates in ball bearings 19, 20, near its upper and lower ends, being extended beneath the lower bearings 20 and carrying a screw 21 which meshes with a wheel 22 of a horizontal shaft 23, rotating in a bearing 24 in a cavity 26 in the ground 25 and carrying a pulley 27. Thus, by rotation of said cylinder, said shaft 26 and pulley 27 are rotated. The current of air traveling upward escapes into and rapidly expands with an air chamber 29, of a cross sectional 30 area considerably greater than that of the space of the upper portion 31 of which converges, said air current then flowing into a stack 32, having at its upper end an elbow 33 carrying a vertical shaft 34 which rotates 35 in bearings 36 supported by spiders 37 within the stack 33, so that said elbow can rotate upon said stack. The elbow carries a director vane 38 and also a cone 41 which converges toward the discharge end of said 40 elbow and is spaced therefrom as shown at 42. By the force of the wind acting upon said vane 38, the elbow is turned to the direction toward which the wind is blowing and the result is that the wind blowing into 45 the wide end of the cone and escaping from the narrow end thereof assists in creating a draft through said stack.

By means of this contrivance, I take advantage of the fact that in general the ground 50 is cooler than the air above it, and, consequently, that air currents flowing through passages in the ground are comparatively cool. The cold air sinks or is drawn into said passages and flows upward, the air in 55 the tubes 1 nearer to the surface of the ground, and, therefore, being warmer, ascending creating a draft. Also the air in the air or expansion chamber 29 and in the stack due to its relatively sudden change in 60 temperature and consequent rapid expansion, rises and flows out from the stack, this action being increased by the relative increased area of the interior of chamber 29 over the area of the space 7; this expansion

draft being also assisted by the wind, as 65 already explained. Consequently, there is imparted a constant revolution to the cylinder 8 rotating the shaft 15 and the pulley 27.

Having thus described my invention, what I claim as new and desire to protect by 70 Letters Patent is:—

1. An atmospheric power generator including a plurality of open tubes disposed with their discharge ends radiating from a common point and embedded in the earth with their receiving ends communicating with the atmosphere at a point below their discharge ends, a cylindrical vertically disposed chamber into which the discharge ends of said tubes discharge, a power cylinder 75 rotatably mounted on a vertical axis within said chamber and of a diameter less than that of said chamber, providing a restricted air passage between the periphery of said cylinder and said chamber wall, a series of vanes 80 carried by and projecting outwardly from the periphery of the cylinder, said vanes being disposed spirally longitudinally of the cylinder with their edges in extreme close proximity to the inner surface of said chamber wall, an expansion chamber communicating directly with the upper end of said restricted air passage and of a cross sectional area considerably greater than that 90 of said air passage, a stack extended vertically from said expansion chamber, an elbow rotatably supported on the upper end of said stack, a direction vane carried by said elbow, and a cone around said elbow 95 and converging toward its discharge end and 100 spaced therefrom.

2. In combination with a subterranean passage opening at its opposite end at the surface of the ground, a cylindrical vertically disposed chamber positioned over the 105 discharge end of said passage and into which the same discharges, an elongated cylinder closed at its opposite ends and mounted to rotate on a vertical axis within said chamber, said cylinder being of a diameter slightly less than that of said chamber, providing between said cylinder and chamber wall a relatively long restricted air passage, a plurality of vanes radiating from the periphery of the cylinder and disposed in 115 longitudinal spirals about the same with their free edges in close proximity to the surface of said chamber wall, an expansion chamber communicating directly with said air passage and positioned directly thereabove, said expansion chamber having a cross sectional area considerably greater 120 than that of said air passage, and a stack extending vertically from said chamber.

In testimony whereof I have signed my 125 name to this specification.

DEIANA DOMENICO.
